CLAIM

The ornamental design for a rectifier busbar, as shown and described.

DESCRIPTION

FIG. 1 is a perspective view of a first embodiment of a rectifier busbar;

FIG. 2 is a right side view of the rectifier busbar shown in FIG. 1;

FIG. 3 is a left side view of the rectifier busbar shown in FIG. 1;

FIG. 4 is a rear view of the rectifier busbar shown in FIG. 1;

FIG. 5 is a front view of the rectifier busbar shown in FIG. 1;

FIG. 6 is a top view of the rectifier busbar shown in FIG. 1; FIG. 7 is a bottom view of the rectifier busbar shown in FIG. 1;

FIG. 8 is a perspective view of a second embodiment of the rectifier busbar;

FIG. 9 is a right side view of the rectifier busbar shown in FIG. 8;

FIG. 10 is a left side view of the rectifier busbar shown in FIG. 8;

FIG. 11 is a rear view of the rectifier busbar shown in FIG. 8;

FIG. 12 is a front view of the rectifier busbar shown in FIG. 8;

FIG. 13 is a top view of the rectifier busbar shown in FIG. 8; and,

FIG. 14 is a bottom view of the rectifier busbar shown in FIG. 8.

The broken lines depict portions of the rectifier busbar which form no part of the claimed design.
